UNITED STATES PATENT OFFICE.

OSCAR MARTIN CARTER, OF HOUSTON, TEXAS.

COMBINATION LIFTING AND LOWERING TOOL FOR DRILLS.

Application filed December 27, 1926. Serial No. 157,313.

This invention relates in general to means for raising and lowering well drills and more particularly to a combination lowering and lifting tool especially designed for use in lowering and raising a collapsible rotary drill of the type forming the subject matter of my co-pending application Serial No. 648,141, filed June 27, 1923.

The object of the invention is to provide a tool of this character which securely grips the drill during the lowering operation and during the lifting operation and yet is readily and easily engageable with and disengageable from the drill. In this connection it is to be understood that after the drill has been lowered to its proper place in the well it becomes necessary to disengage the lowering tool therefrom. The present invention provides for automatic disengagement of the jaws of the tool from the head of the drill and also for automatic locking of the jaws in disengaged position. And yet when used as a lifting tool the jaws automatically engage the head of the drill and are automatically locked in such engagement. This advantageous action is had without necessitating any tedious or difficult manipulations.

Another object is to provide a combined lowering and lifting tool of this character which is of simple, durable and rugged construction, not liable to become bent, broken or disordered by the severe usage of actual working conditions, and easy and comparatively inexpensive to manufacture.

Another object is to provide a well drill adapted to facilitate the operation of the means for raising and lowering the drill.

Other objects and advantages reside in certain novel features of the construction, arrangements and combinations of parts which will be hereinafter more fully described and particularly pointed out in the appended claims, reference being had to the accompanying drawings, forming a part of this specification and in which:

Figure 1 is a view in elevation showing the tool in use in lowering the drill into the well.

Figure 2 is a similar view showing the lowering tool tripped to release the drill.

Figure 3 is a detail view of the control rod employed for opening the jaws, together with the associated connecting piece between the jaws,

Figure 4 is a detail view of the gravity lock for holding the jaws open.

Figure 5 is a horizontal section on line 5—5 of Fig. 4.

Figure 6 is a bottom plan view of the jaws,

Figure 7 is a vertical section of the tool with its jaws shown open,

Figure 8 is a similar view showing a different position of the parts with the jaws closed,

Figure 9 is a horizontal section on line 9—9 of Fig. 8,

Figure 10 is a detail showing the latch member in locked operative position,

Figure 11 is a similar view with the latch shown locked when the tool is to be used as a raising tool, and

Figure 12 is a side elevation of the upper portion of a drill.

Referring to the drawings, the numeral 1 designates generally an expandable and contractible rotary drill of the type forming the subject matter of my application filed June 27, 1923, Serial Number 648,141.

This drill 1 is designed to be lowered down through the drill stem 2 and expanded and locked in position and also may be collapsed and lifted up through the stem whenever desired. As usual this drill has a weight 3 and also a control bar 4 at the upper end of which a head 5 is provided, the head 5 being rigid with the control bar 4. As shown this head 5 has a downwardly presented shoulder 5^a and also has its upper surface 5^b rounded off.

The present invention proposes the provision of longitudinal grooves 6 in the periphery of the weight 5 to insure rapid and easy passage of the mud away from the lowering and lifting means and to prevent mud or sediment from building up on the weight and clogging or interfering with the action of the tool.

The combination lowering and lifting tool constituting this invention comprises a pair of similar jaws 7 and 8, each having the general form of half a hollow cylinder. Intermediate their ends the jaws 7 and 8 have transversely alined slots 9 and 10 in which the ends 11 and 12 of a connecting piece designated generally at 13 is fitted, the slot ends of the connecting piece being so shaped to permit the jaws to oscillate on the ends of the connecting piece. Pivot pins 14 con-

strain the jaws to oscillating or pivotal movement about a horizontal axis. The vertical edges of the jaws are spaced from each other to afford the necessary clearance and the outer peripheries of the jaws taper from the points of their connection with the connecting piece to their upper ends as indicated at 7^a and 8^a respectively. The lower ends of the jaws may be rounded off slightly.

16 The jaws are suspended upon a cable or other suitable lowering line (not shown) by means of a control rod 15 slidably fitted in an opening provided therefor in the connecting piece 13 and extending axially of 15 the tool between the jaws 7 and 8. The upper end of the rod 15 is adapted for connection with the cable and adjacent the lower ends of the rod a shoulder 16 is provided and is designed to engage the connecting 20 piece 13 to limit the upward movement of the rod relative to the tool.

Upwardly facing shoulders 17 are formed on the jaws adjacent to but slightly spaced upwardly from the lower ends thereof, said shoulders 17 being designed to engage the downwardly presented shoulder 5^a on the head of the drill whereby to effectively grip the drill. Inclined or bevelled guiding surfaces 18 are provided on the extreme 30 lower ends of the jaws to facilitate the passage of the jaws over the head 5.

Removable inverted J-shaped latches designated generally at 19 and 19^a are carried respectively by the jaws 7 and 8 and 35 are cooperable with keepers formed in the opposed jaw. These latches each has a long leg 21 slidably fitted in a slot 22 provided in the jaw carrying the latch, the slot opening through the bottom of the jaw and the 40 leg 21 projecting down below the jaw when in latching position, see Figs. 1 and 10. The slots 22 are enlarged laterally above the lower end of the jaw and open out through the adjacent vertical face or edge of the jaw 45 as indicated at 25^a. Through this lateral enlargement of the slot the cross member 23 of the latch extends the cross member projecting beyond the jaw and carrying at its outer end the depending short leg 24 of the 50 latch. A coiled spring 25 is carried by each jaw above its latch to limit the upward movements of the latch and to hold it yieldably in locking position. The keeper 20 is formed by slotting the jaw in which it is 55 formed circumferentially inwardly from its vertical face as at 26 and then downwardly as at 27.

A lock is provided to automatically lock the jaws in position to disengage the drill 60 and this lock preferably comprises a lock sleeve 28 slidably fitted on the upper end of the control rod 15 and having a socket 29 in its lower portion designed to receive and rather snugly fit the upper tapered end portions 65 7^a and 8^a of the jaws when the upper

ends of the jaws are brought together. This sleeve 28 has a central bore 28^b communicating with socket 29 and a plurality of radial ducts 28^a lead from bore 28^b through the periphery of the sleeve to provide an escape 70 for thick mud and sand which accumulates in the sleeve in its downward movement, this escape facilitating the engagement of the sleeve with the top of the jaws 7 and 8.

Means is provided to swing the jaws on their pivots 14 to bring the shoulders 17 toward each other and into engagement with the shoulder 5^a of the head 5 of the drill and this means preferably comprises two tapered or conical expanding collars 30 and 30^a fixedly connected to the rod 15 on opposite sides of member 13 and cooperable with correspondingly formed surfaces 40 and 41 and 40^a and 41^a provided on the jaws 7 and 8. When the shoulders 17 have been spread apart by lowering of rod 15 the collar 30 is accommodated in recesses 42 and 43, in Fig. 7. When the jaws have been closed as shown in Fig. 8 by raising of rod 15 collar 30^a is located in recesses 42^a and 43^a.

The device in use as a lowering tool is shown in Figure 1. The jaws 7 and 8 are locked in closed position by the latches 19 and 19^a and in such position their shoulders 17 engage under the shoulder 5^a of the head 5 of the drill. The lock sleeve 28 is maintained elevated as its lower end rests on the spread upper ends of the jaws. The weight of the tool and drill is carried by the lowering line since at this time the shoulder 16 of the rod engages the underside of the connecting piece 13. When the drill has reached the proper position in the drill stem and is expanded and locked in such position the lowering tool is dropped down on the drill so that the legs 21 of the latches strike the weight 3 of the drill whereby to release the latches. The rod 15 also lowers relative to the tool which causes the conical collar 30^a to engage walls 40^a and 41^a and open the jaws. Furthermore the lower bevelled end 18 of the tool coacts with the beveled upper end 3^a of the weight 3 to spread the lower ends of the jaws and disengage the shoulders 17 from the shoulder 5^a. This brings the upper ends of the jaws together and the lock sleeve 28, which is heavy, drops downwardly so that its socket 29 telescopes over the upper end of the jaws thereby holding the jaws in open position. The lowering tool may be raised out of the well and the drilling carried on.

When the device is used as an elevating or lifting tool the long sleeve 28 is taken off and the tool is then lowered into the well until the lower ends of the jaws engage the rounded surface 5^b of the head 5 of the control bar 4. The coaction of the guiding surfaces 18 with this rounded surface 5^b results

in automatic spreading of the jaws so that the jaws may be and do pass down over the head 5 to bring the shoulder 17 below the shoulder 5^a, of the head 5. Then when the cable is elevated the conical collar 30 coacts with the surfaces 40 and 41 to automatically swing the jaws to closed position and cause shoulders 17 to engage the shoulder 5^a of the head.

10 Preferably the latches 19 and 19^a are employed only when the combination tool is passed down through very thick mud, to prevent the possibility of undesirable release of the drill at such a time. However, the latches may be employed as often as may be desirable.

I claim:—

1. A tool of the character described comprising a pair of jaws, means for pivotally connecting the jaws to each other intermediate their ends, said jaws having their lower ends adapted to engage a drill, and a latch for holding the lower ends of the jaws closed, said latch having a portion projecting forwardly of the jaws and engageable with the drill to release the latch.

2. A tool of the character described comprising a pair of jaws, means for pivotally connecting the jaws to each other intermediate their ends, said jaws having their lower ends adapted to engage a drill, a latch for holding the lower ends of the jaws closed, said latch having a portion projecting forwardly of the jaws and engageable with the drill to release the latch, and a lock cooperable with the upper end of the jaws for holding the lower ends of the jaws open, said lock being biased to automatically have locking engagement with the upper ends of the jaws when said upper ends are brought together.

3. A tool of the character described comprising a pair of jaws, a connecting piece extending between the jaws and pivotally connected thereto, a control rod slidably extended through the connecting piece and having means cooperable therewith to limit the upward movement of the rod relative to the connecting piece, the forward ends of the jaws having means adapted to grip a drill and also having inclined guiding surfaces to spread the jaws and guide them onto the drill, a latch for holding the jaws closed, said latch having a release member projecting beyond the tool and engageable with the drill, and co-operating means on the rod and jaws for closing the jaws.

4. A tool of the character described comprising a pair of jaws, a connecting piece extending between the jaws and pivotally connected thereto, a control rod slidably extended through the connecting piece and having means cooperable therewith to limit the upward movement of the rod relative to the connecting piece, the forward ends of the

jaws having means adapted to grip a drill and also having inclined guiding surface to spread the jaws and guide them onto the drill, a spring pressed latch for holding the jaws closed, said latch having a release member projecting beyond the tool and engageable with the drill, and cooperating means on the rod and jaws for closing the jaws, and comprising a tapered expanding collar on the rod, the jaws having correspondingly formed cooperating surfaces.

5. A tool of the character described comprising a pair of jaws, a connecting piece extending between the jaws and pivotally connected thereto, a control rod slidably extended through the connecting piece and having means cooperable therewith to limit the upward movement of the rod relative to the connecting piece, the forward ends of the jaws having means adapted to grip a drill and also having inclined guiding surface to spread the jaws and guide them onto the drill, a latch for holding the jaws closed, said latch having a release member projecting beyond the tool and engageable with the drill, and a lock sleeve slidably mounted on the upper end of the rod and having a socket adapted to receive the upper ends of the jaws when said upper ends are brought together to hold the lower ends of the jaws open.

6. A tool of the character described comprising a pair of jaws pivotally interconnected intermediate their ends, the forward portions of the jaws having shoulders designed to have gripping engagement with the drill and also having inclined surfaces cooperable with the drill to spread the jaws, and a latch for holding the jaws together, said latch having a release member projecting beyond the jaws and engageable with the drill.

7. A tool of the character described comprising a pair of jaws pivotally interconnected intermediate their ends, the forward portions of the jaws having shoulders designed to have gripping engagement with the drill and also having inclined surfaces cooperable with the drill to spread the jaws, and an inverted J-shaped latch slidably mounted on one of the jaws, said latch having a long leg projecting down below the jaws, a cross member projecting laterally beyond the jaw and a short leg depending from the cross member, said other jaw being slotted to define a keeper for the cooperable portion of the cross member and for the short leg.

8. A tool of the character described comprising a pair of jaws, means for pivotally connecting the jaws to each other intermediate their ends, such jaws having their lower ends adapted to engage a drill and a lock cooperable with the upper ends of the jaws for holding the lower ends of the jaws open, said lock being adapted to automatically

ecally have locking engagement with the upper ends of the jaws when said upper ends are brought together.

9. A tool of the character described comprising a pair of jaws, a connecting piece extending between the jaws and pivotally connected thereto, a control rod slidably extended through the connecting piece and having means cooperable therewith to limit the upward movement of the rod relative to the connecting piece, the forward ends of the

jaws having means adapted to grip a drill and also having inclined guiding surfaces to spread the jaws and guide them onto the drill, cooperating means on the rod and jaws for closing the jaws, and a lock sleeve slidably mounted on the control rod and having a socket engageable with the upper end of the jaws for holding the lower ends of the jaws open. 15

OSCAR MARTIN CARTER.
